Erdick Nelson, Walworth, Wis., assignor to Square
Manufacturing Company, a corporation of Illi-
nois

Application May 13, 1950, Serial No. 9,924

Term of patent 14 years

(Cl. D52—3)

To all whom it may concern:

Be it known that I, Erdick Nelson, a citizen of the United States, residing at Walworth, in the county of Walworth and State of Wisconsin, have invented a new, original, and ornamental Design for a Beverage Dispensing Machine, of which the following is a specification, forming part thereof.

Figure 1 is a perspective of a beverage dispensing machine, showing my new design;

Figure 2 is a top plan view of the machine;

Figure 3 is a front elevational view of the machine; and

Figure 4 is a side elevational view of the machine.

I claim:
The ornamental design for a beverage dispensing machine, as shown.

ERDICK NELSON.
